CARBURETOR

Bernard C. Phillips, Toledo, Ohio, assignor to The Tillotson Manufacturing Company, Toledo, Ohio, a corporation of Ohio

Application March 17, 1943, Serial No. 479,532

1 Claim. (Cl. 261—39)

This invention relates to carburetors and more especially to aviation carburetors of relatively small capacity.

In carburetors used at ground level elevations, little effect on fuel mixtures is encountered due to the changes in air or atmospheric pressure. In airplanes the carburetor must function properly at ground levels, at very high altitudes, and at all intermediate positions. In order to obtain the proper mixture ratio, that is the ratio of fuel to air, at all altitudes it is necessary to provide special means to compensate for the change in the density of the air. Numerous devices are in use at the present time that accomplish this purpose, but all of these devices are used in connection with carburetors for large engines. Many attempts have been made to use the same types of control devices as used on large carburetors, only in smaller sizes. None of these devices have proven successful on the small carburetor.

One of the objects of my invention is to provide an altitude mixture control that will operate properly on a small capacity carburetor.

Another object of my invention is to provide an altitude mixture control that can be used with or without a supercharger.

Another object of my invention is to provide an altitude mixture control that is simple, durable, dependable and inexpensive.

My invention will be best understood from the detailed description and claim which follows reference being made to the accompanying drawings in which a preferred embodiment of my invention is shown by way of example in which:

Fig. 1 is a front elevation of a carburetor embodying my novel invention.

Fig. 2 is a top plan view of a carburetor embodying my invention.

Fig. 3 is a sectional view taken along line 3—3 of Fig. 2.

Fig. 4 is a sectional view taken along line 4—4 of Fig. 2.

Fig. 5 is a sectional view taken along line 5—5 of Fig. 2.

Fig. 6 is an enlarged sectional view of a portion of the carburetor shown in Fig. 4.

Fig. 7 shows a variation of my novel invention.

Referring to the drawings I have shown an aviation carburetor 10 provided with a flange 11 whereby the carburetor is fastened to an intake manifold 12. Air enters the carburetor 10 through the air horn 13 and passes through the venturi 14, where the air is mixed with the fuel, and then flows into the intake manifold 12. A

compensating tube 15 has one end opening into the air intake 13 and the opposite end into the passageway 16. The passageway 16 terminates in a control chamber 17. A sealed metal bellows 18 is located in the control chamber 17. The sealed metal bellows 18 is held in a definite position by means of the adjusting screw 19 which is screwed into the threaded hole 20. After the initial adjustment, the screw 19 is locked and sealed in position. An air flow control 21 is fastened to the lower end of the sealed metal bellows 18 and operates in a restriction or orifice 22 located in the plug 23. The lower end of the pin 21 is provided with a shoulder 24 which operates in the annular hole 25 to serve as a guide for the air flow control pin 21. The air chamber 26 is connected to the annular chamber 27 by means of the passageways 28. A passageway 29 connects the annular chamber 27 to the intermediate chamber 30. The intermediate chamber 30 opens into the Venturi or mixing chamber 14 as shown in Fig. 5, by means of the opening 43.

The carburetor 10 is provided with a fuel inlet 31. Fuel is supplied by means of a fuel pump or other suitable means. The fuel inlet 31 leads into a conventional float bowl where a substantially constant fuel level is maintained by means of a float and lever arrangement. The float 33 is fastened to a lever 34 which is fulcrumed on a pin 35. When the fuel flows into the bowl and reaches the desired level the inlet needle 36 is pushed upward closing the fuel inlet. As the fuel level drops the float 33 drops, thus lowering the arm member 34 which in turn allows the inlet needle 36 to drop which opens the fuel inlet and allows more fuel to enter the float bowl 32. In this way a substantially constant fuel level is maintained in the float bowl 32.

A fuel passageway 37 connects the float bowl 32 to the fuel chamber 38. A fuel passageway 40 in the nozzle 39 transmits the fuel to the nozzle restriction 41. The nozzle restriction 41 is an orifice conventionally used to control the quantity of fuel required.

A passageway 42 connects the control chamber 17 to the float bowl chamber 32.

When air is drawn through the carburetor air intake 13, it flows through the venturi 14 where increased velocity of the air causes a decrease in static pressure. This reduced static pressure produces a suction on the opening 43, which in turn is transmitted to the fuel orifice restriction 41 and also to the air passageway 29. Fuel is then drawn from the float bowl 32 through

the fuel passageway 37 into the fuel chamber 38. From the fuel chamber 38 the fuel flows into the nozzle passageway 40 through the restriction 41 into the auxiliary mixing chamber 30 where it is mixed with a limited amount of air delivered through passage 29. The mixture then flows through the opening 43 into the Venturi or mixing chamber 14. Here the fuel is mixed with more air to form a combustible mixture.

After the proper size of fuel restriction or orifice 41, the amount of air bleed and the outlet 43 have been determined for proper fuel to air mixture ratios, the carburetor will continue to deliver the same mixture ratio as long as the air pressure is not materially changed.

As an airplane leaves the ground and climbs to higher altitudes, the air pressure decreases. The lowered air pressure decreases the density of the air but has little effect on the density of the fuel. For each cubic foot of air flowing through the venturi a given amount of fuel is metered to the air stream regardless of air pressure changes. As the air pressure decreases, the air becomes less dense and the mixture ratio becomes richer with fuel; therefore, some means must be provided to prevent mixtures from becoming too rich at higher altitudes. This is done in large capacity carburetors by the use of a metering pin acting directly in the fuel nozzle which decreases the fuel flow as the air pressure decreases. Quite satisfactory results are obtained on large capacity carburetors by this method; however, these structures have not proven practical in small output carburetors due to the difficulty in development and duplication of such control in combination with the small fuel orifice required.

My invention controls the flow of air that changes the suction on the fuel restriction instead of attempting to vary this restriction. When air is moving through the air horn 13 and venturi 14 the suction at 43 causes air to flow into compensating tube 15 through the passageway 16, into the control chamber 17, and then through the orifice or restriction 22 into the air chamber 26. From the air chamber 26 the air passes through the passageways 28 into the annular chamber 27 and then through the passageway 29 into the intermediate mixing chamber 30. From the intermediate mixing chamber 30 the air from the passageway 29 and the fuel from the nozzle restriction 41 pass through the opening or passageway 43 and mix with the main air supply entering through the venturi to form a combustible mixture of fuel and air which is drawn into the intake manifold 12. Since the suction on the passageway 43 remains constant for a given flow of air the suction in the intermediate mixing chamber 30 also remains constant. The amount of fuel drawn through the nozzle restriction 41 will depend upon the amount of air entering the intermediate mixing chamber 30 from the passageway 29. My invention provides a metering pin located in the orifice 22 to control the flow of air to the intermediate mixing chamber 30. The greater the flow of air from the control chamber the less the suction in the intermediate mixing chamber 30 and hence less fuel flows from the nozzle restriction 41.

The sealed metal bellows 18 expands as the pressure in the control chamber decreases and contracts as the pressure increases. This ex-

pansion and contraction of the bellows causes the conical shaped air flow control pin 21 to move up and down in the orifice 22 and the varying diameter of the control pin 21 changes the effective area of the opening in the orifice 21, thus regulating the flow of air through the orifice. When my novel carburetor is used at higher altitudes the pressure in the air horn 13 decreases. This pressure is transmitted to the air control chamber 17 and causes the bellows to expand which moves the air flow control pin so that more air is permitted to enter the intermediate chamber 30, thus reducing the suction on the fuel nozzle restriction 41 and maintaining the proper mixture ratio.

A passageway 42 connecting the control chamber 17 and the sealed float bowl chamber provides a means for equalizing the pressure in the air horn 13 and the float bowl chamber 32.

My carburetor can also be used in connection with a supercharger or ram pressure applied to the intake of the carburetor. In such an arrangement the pressure produced would be transmitted to the control chamber 17 through the compensating tube 15 and the passageway 16. This pressure in the control chamber causes the bellows 18 to contract or partially collapse, which raises the air flow control pin 21, thus decreasing the flow of air through the orifice 22. This produces a greater suction in the intermediate mixing chamber 30 and as a result more fuel is drawn from the fuel supply through the nozzle restriction 41. Thus a proper fuel mixture is maintained regardless of the pressure.

Fig. 7 discloses another form of my invention. In this form of my invention the nozzle restriction 45 is at the lower end of the nozzle 46. Fuel flows from the float bowl 32 through the passageway 37 into the fuel chamber 38. The fuel then flows through the nozzle restriction 45 into the auxiliary mixing chamber 47 where air from the air passageway 29 enters through the holes 48. The flow of air from the air passageway 29 is controlled as previously described. The flow of air through the holes 48 controls the suction on the fuel restriction 45 in the nozzle for providing proper fuel mixture ratios as described. This form of applicant's novel invention varies from the one described above in that the auxiliary mixing chamber 47 is located within the nozzle 46, instead of between the nozzle and the venturi as shown in Fig. 5.

From the above description it will readily be seen that my novel mixture control device can be used on carburetors of small capacity as well as on large ones and that it will operate properly at all altitudes with or without the use of a supercharger.

While I have described the details of two forms of my invention, I do not wish to be limited to the particular forms shown and described as it will be apparent that many modifications therein can be made without departing from the scope of my invention as set forth in the appended claim.

Having thus described my invention what I claim is:

In a carburetor, an air inlet, a mixture passageway, a float bowl, a mechanism for maintaining a constant fuel level in said float bowl, a fuel passageway extending from said float bowl below said fuel level, a fuel spray orifice in said fuel passageway, an intermediate mixing chamber between said fuel orifice and said mixture passageway having an outlet in line with said orifice, a

control chamber, a plurality of air passageways communicating with said control chamber whereby the pressure in said float bowl and said control chamber are equalized with pressure in said air inlet, an air passageway extending from said control chamber to said intermediate mixing chamber, a barometric pressure responsive control means mounted in said control chamber, an orifice in said last mentioned air passageway, an air flow control valve directly mounted on said pressure responsive control means, said pressure

responsive means adapted to move said flow control valve axially in said second orifice, said axial motion of said air flow control valve varying the effective opening of said second orifice whereby the air flow to said auxiliary mixing chamber is automatically controlled, thereby varying the suction in the intermediate mixing chamber to compensate for variations in fuel mixtures caused by different pressures in said air intake.
